SNAP ACTION SWITCH

George O. Puerner, Indianapolis, Ind., assignor to
 P. R. Mallory & Co., Inc., Indianapolis, Ind., a
 corporation of Delaware

Application February 11, 1947, Serial No. 727,842

6 Claims. (Cl. 200—67)

1

This invention relates to snap action switches and, more particularly to switches of the type which comprise an actuating member, an actuated member and a snap action spring interconnecting said members.

It is common practice, in snap action switches, to provide an actuated member carrying a movable contact which is adapted to be moved, by snap action, between a pair of fixed contacts or between a single fixed contact and a stop member. In accordance with the prior art, a movable actuating member is provided for moving a snap action spring which, in turn, effects snap action of the actuated or contact-carrying member. With such constructions, when the actuating member is moved to a first critical position, the direction of thrust of the snap action spring is abruptly changed thereby moving the actuated member and the movable contact thereon, by snap action, from its initial position to a second position. When the actuating member is moved to a second critical position, the direction of thrust of the actuating spring is again abruptly changed to return the movable contact to its initial position by snap action.

It was at first proposed to utilize a coil spring for obtaining the described snap action. However, the characteristics of such coil springs were not sufficiently uniform to provide reliable operation over extended periods of time. Further, such coil springs were difficult to adjust and somewhat critical in operation. It was later found that the results could be considerably improved by substituting a U-shaped snap action spring for the coil spring, this U-shaped spring being held in suitable bearings on the actuating member and actuated member, respectively. Although this type of snap action spring gave superior results as compared to the use of a coil spring, considerable difficulty has heretofore been experienced in providing bearings for properly supporting the U-shaped spring. In this connection, it will be understood that the provision of suitable bearings is a matter of considerable importance as the movable contact must be moved by snap action between its fixed positions smoothly and uniformly when the critical operating positions of the actuating member are reached. Accordingly, any irregularity in the function of the bearings is almost certain to cause faulty operation of the switch.

Prior to this invention, two types of bearings for the U-shaped snap action switch have been proposed. According to the first proposal, a lost motion connection is provided at the bearing sur-

2

faces where the spring is connected to the actuating member and actuated member, respectively. The resulting relative movement between the snap action spring and the members to which it is secured is disadvantageous in that it tends to change the operating positions of the switch with resultant erratic operation thereof. The second proposal involves the use of so-called knife edge bearings. According to this construction, tongues are provided at the respective ends of the snap action spring which fit into slots in the actuating member and actuated member, respectively, and shoulders are provided on the spring which engage the surfaces of the aforesaid members adjacent the slots therein. Each bearing, therefore, has a first bearing surface or pivot line where one side of the member is engaged by the shoulders and a second pivot line where the other side of the member is engaged by the tongue at the inner end of the slot. These pivot lines are spaced apart a distance determined by the thickness of the member, the snap action spring pivoting on one of these bearing surfaces when the switch is in one part of its operating range and on the other bearing surface when the switch is in a different part of its operating range. This type of bearing does not function satisfactorily and is somewhat erratic in operation due to the aforesaid double pivoting action. In addition, it has been found that such switches require a long wearing in period before satisfactory operation can even be approximated.

It is an object of this invention to provide a snap action spring mounted in bearings in which the engaging surfaces of the spring and the members associated therewith define straight lines constituting, respectively, knife edges for the spring.

It is a further object of the invention to provide a snap action switch in which the spring pivots along a single straight line in each bearing.

It is a still further object of the invention to provide a snap action switch in which complete satisfactory operation may be obtained without the necessity of operating the switch for a considerable wearing in period before actual use thereof.

It is a still further object of the invention to provide a switch which functions immediately when the actuating member reaches its respective critical positions.

The invention further contemplates the provision of a snap action switch which is simple in construction, of low cost, and reliable in operation over extended periods of time.

Other objects of the invention will be apparent from the following description and accompanying drawings taken in connection with the appended claims.

The invention accordingly comprises the features of construction, combination of elements, arrangement of parts, and methods of manufacture referred to above or which will be brought out and exemplified in the disclosure hereinafter set forth, including the illustrations in the drawings, the scope of the invention being indicated in the appended claims.

For a fuller understanding of the nature and objects of the invention as well as for specific fulfillment thereof, reference should be had to the following detailed description taken in connection with the accompanying drawings, in which:

Figure 1 is a perspective view of a novel snap action switch;

Figure 2 is a plan view of the snap action switch shown in Figure 1;

Figure 3 is a sectional view taken along the line 3—3 of Figure 2; and

Figure 4 is a sectional view, partially broken away, taken along the line 4—4 of Figure 3.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Referring now to the drawings in detail, the novel snap action switch comprises an actuated member 10 and an actuating member 11 secured in a rivet type stack assembly 12 which is mounted on a support 13 as by a screw 14. The actuated member carries a movable contact 15 at the free end thereof which cooperates with fixed contact means 16. In the embodiment shown, the fixed contact means comprises a pair of fixed stationary contacts 17, 18 which are mounted, respectively, on stationary contact arms 19. However, in some embodiments of the invention, only one fixed contact is utilized, such as a fixed contact 17, and the fixed contact 18 may be replaced by a suitable stop for limiting the movement of the actuated member 10.

The central portion of the actuated member is cut out, as indicated at 20, and a bearing structure 21 is provided adjacent the free end thereof which will be more fully described hereinafter.

The actuating member 11 comprises a strip 25 of resilient material which is mounted in the stack assembly 12 and a rigid member 26 is secured to the free end of the resilient strip 25 as by a rivet 27. An actuator is mounted in the rigid member 26 and this actuator preferably consists of an adjusting screw 28 having a bushing 29 for holding it in position and providing an additional mechanical connection between the rigid member 26 and the resilient strip 25. A lock nut is provided for fixing the adjusting screw in the bushing. A bearing structure 30, which is generally similar to bearing 21, is positioned at the free end of the actuating member 11 and, as shown, a generally U-shaped snap action spring 31 is mounted in the bearings 21 and 30.

The bearing 30 comprises a pair of spaced projections 32 which define a slot 34 and these projections have flat bearing surfaces 35 on opposite sides of the slot. An ear 36 is struck up from

the rigid member 26 at the inner end of the slot and this ear has a pair of inclined surfaces 37, 38 each of which is disposed at an acute angle with respect to the bearing surfaces 35. In accordance with the invention, the surfaces 37, 38 define a knife edge 39 which is positioned in the plane of the flat bearing surfaces 35 and extends along the inner end of the slot 34.

The structure of the bearing 21 is generally similar to that of bearing 30 and this structure comprises a knife edge 42 defined by inclined surfaces 43, 44 of an ear 45 which is struck up from the actuated member 10. The knife edge 42 extends along the inner edge of a slot 46 and lies in the plane of flat bearing surfaces 47, 48 which are disposed at opposite sides of the slot.

The snap action spring 31 has tongues 50 at the respective opposite ends thereof, each tongue being flanked by shoulders 51 which are spaced from the ends of the aforesaid tongues 50, respectively. These tongues are of the proper width to fit into the respective slots 34 and 46 and, as shown by Figure 3, these tongue portions engage the knife edges 39 and 42, respectively. The shoulders 51 engage the respective bearing surfaces 35 and 47 and thereby hold the spring in position within the slots and against the knife edges 39 and 42. With respect to the bearing 21, it will be seen that the line of engagement of the shoulders 51 with the bearing surfaces 47 is substantially in alignment with the knife edge 42 which engages the tongue 50, knife edge 42 being in the same plane with the bearing surfaces. Any misalignment between the knife edge 42 and the knife edge formed by the shoulders 51 of spring 31 aligned on the bearing surfaces 47 is caused by the thickness of the spring 31 which in the present invention is a minimum and is relatively small compared with the thickness of either the actuating member 11 or the actuated member 10. Therefore, for all practical purposes the knife edge 42 and the other described knife edge for the concerned end of the spring 31 are substantially in alignment. Similarly, with respect to the bearing 30, the line of engagement of the shoulders 51 with the bearing surfaces 35 is in alignment with the knife edge 39 which engages the adjacent tongue 50. Accordingly, the engaging surfaces of the spring and the respective bearings define straight lines constituting, respectively, true knife edge bearings for the spring. Further, due to the angular position of the surfaces 37, 38 and 43, 44 only the knife edges 39, 42 of the respective struck up ears 36, 45 engage the spring in any position of the actuated member 10. As a result, the spring 31 rests on effectively true knife edge bearings and satisfactory operation of the switch is obtained without any wearing in period and without the assembly or the permanently fastening of the parts together.

It is important that the radius r of the curved portion of the spring be less than half the distance D between the bearings in order that the legs of the U-shaped spring may be divergent so that the spring forces itself into engagement with the bearing surfaces thus holding the spring in assembled position at all times without the necessity of a permanent mechanical connection between the spring and the members 10 and 11.

With the parts in the positions shown by Figure 3, upward movement of the actuator 28 to a first critical position causes the actuated member 10 to move downwardly by snap action thus opening contacts 15, 17 and closing con-

tacts 15 and 18. Thereupon, downward movement of the actuator to a second critical position causes the actuated member 10 to move upwardly by snap action thus opening contacts 15, 18 and closing contacts 15 and 17. During operation of the switch in this manner, the novel knife edge bearings of this invention cause the snap action spring 31 and actuated member 10 to move smoothly between their predetermined positions. Further, the fact that each bearing surface is effectively a single straight line prevents erratic operation of the switch and eliminates drift of the critical operating positions of the actuating member.

While the present invention, as to its objects and advantages, has been described herein as carried out in specific embodiments thereof, it is not desired to be limited thereby but it is intended to cover the invention broadly within the spirit and scope of the appended claims.

What is claimed as new and desired to be secured by Letters Patent is:

1. In a snap action switch, an actuating member and an actuated member, each of said members having a slotted portion with flat bearing surfaces at the respective sides of said slot, an inclined surface integrally formed of said members in said slotted portion, a knife edge being formed on said inclined surface disposed in the plane parallel to said bearing surfaces, a U-shaped snap action spring having tongues at the respective end thereof which extend through said slots and engage said knife edges, and shoulders formed on said spring for engaging said bearing surfaces whereby said spring engages each of said members along a line slightly offset from one of said knife edges vertically and defined by the engaged portions of said shoulders and said bearing surfaces said offset being negligible as compared with the thickness of either one of said members.

2. In a snap action switch, an actuating member and an actuated member, each of said members having a flat bearing surface with a central slot formed therein, struck-up means defining a knife edge which is positioned in the plane of said bearing surface and extends along the inner end of said slot, a snap action spring having, at each end thereof, a tongue extending through one of said slots and engaging said knife edge, and shoulders at opposite sides of said tongue for engaging said bearing surface along a line offset from said knife edge vertically a distance determined by the relatively small thickness of said spring compared with that of said actuating member.

3. In a snap action switch, an actuating member and an actuated member, a knife edge bearing on each of said members, and a snap action spring mounted in said bearings having a tongue at each end thereof which is flanked by side shoulder portions, each bearing comprising spaced projections having flat bearing surfaces thereon which are engaged, respectively, by the shoulders on said spring, and a struck up portion defining a knife edge which is positioned between and in the plane of said bearing surfaces, said knife edge being engaged by the tongue on said spring, whereby said spring intersects a plane defined by the knife edge and the line of engage-

ment between said shoulders and said bearing surfaces.

4. In a snap action switch, an actuating member and an actuated member each having a slot therein and flat bearing surfaces at opposite sides of each slot, a struck up ear at the inner end of each slot, each ear having inclined surfaces which are disposed, respectively, at acute angles with respect to said bearing surfaces thereby defining a knife edge extending along the inner end of said slot, said knife edge being disposed in the plane of said bearing surface, a snap action spring having tongues at the respective ends thereof which extend through said slots and engage said knife edges, and shoulders at opposite sides of said tongues, respectively, which engage said bearing surfaces along straight lines which are in a plane, respectively, with said knife edges.

20 5. In a snap action switch, an actuating member and an actuated member each having a slot therein and flat bearing surfaces at opposite sides of each slot, a struck up ear at the inner end of each slot, each ear having inclined surfaces which define a knife edge lying in the plane of said bearing surface, and a generally U-shaped snap action spring having tongues at the respective ends thereof which extend through said slots and engage said knife edges, and shoulders on said spring for engaging said bearing surfaces along straight lines which are in the same plane, respectively, with said knife edges, the surfaces defining said knife edges forming acute angles with the adjacent tongue portion of said spring in all positions of the actuating member.

30 6. In a snap action switch, an actuated member carrying a movable contact, fixed contact means cooperating with said movable contact, an actuating member including a resilient spring and a rigid member attached to the free end of said spring arm, an actuator secured to said rigid member, spaced projections extending from said actuated member and said rigid member, respectively, said projections defining slots having flat bearing surfaces at opposite sides thereof, a struck up ear at the inner end of each slot, each ear defining a knife edge lying in the plane of the adjacent bearing surfaces, and a generally U-shaped snap action spring having tongue portions which extend through said slots and engage said knife edges together with shoulders which engage said bearing surfaces, respectively, the engaging surfaces of said spring and said members defining straight lines constituting, respectively, knife edge bearings for said spring.
